UNITED STATES PATENT OFFICE.

CHRISTOFFER A. CHRISTENSEN, OF ORETOWN, OREGON.

ORE-CONCENTRATOR.

SPECIFICATION forming part of Letters Patent No. 668,980, dated February 26, 1901.

Application filed March 10, 1900. Serial No. 8,150. (No model.)

To all whom it may concern:

Be it known that I, CHRISTOFFER A. CHRISTENSEN, of Oretown, in the county of Tillamook and State of Oregon, have invented a 5 new and useful Improvement in Ore-Concentrators, of which the following is a specification.

My invention relates to ore-concentrators, especially to that class in which a vibrating 10 riffle-pan is employed; and it has for its object the construction of an apparatus of this character which will operate to effectively concentrate the ore and which will be of comparatively few and simple parts.

15 The invention consists in certain details of construction of the riffle-pan and certain arrangements of the same in relation to other parts of the apparatus, which I shall first describe and then particularly claim.

20 Reference is to be had to the accompanying drawings, forming part of this specification, in which like characters of reference indicate corresponding parts in all the views.

Figure 1 is a side elevation of my improved 25 ore-concentrator, parts being broken away. Fig. 2 is a transverse section thereof, and Fig. 3 is a perspective view of a portion of the riffle-pan shown detached.

Referring to the drawings, A designates the 30 preferably wooden framework of the apparatus, from whose upper side timbers depend steel spring-hangers B, four in number, and attached at their lower ends to the metal supporting-frame C, in which the riffle-pan D is 35 adapted to sit.

At one side of the framework A, in the end uprights A', is journaled a shaft E, which has a pulley E^X at one end, whereby it is operated, and a fly-wheel E' at the other end, and 40 is provided with eccentrics E², which work in loops or seats formed on one end of the straps E³, the said straps at their other ends being securely fastened to bars F, which extend from side to side of the riffle-pan D and serve 45 to stiffen or brace the same.

In its specific construction the riffle-pan D is a sheet-metal trough having flaring sides D', and its bottom and sides are bent, as shown particularly in Fig. 1, to form riffles 50 D², and the bottom of the pan slopes from the top of one riffle to the bottom of the next below and is formed with a line of perforations D³ directly in front of and at the bottom of each riffle. Inclined triangular baffle or stop 55 plates G extend from each side edge of the

pan at each riffle and terminate at the bottom of the pan, as shown, the adjacent lower edges of the plates being spaced from each other to provide a middle passage-way for the ore. The plates G prevent the ore from overflowing the riffles at the corners thereof. It is understood that the pan D is held in an inclined position, the hangers at the discharge end of the pan being longer than those at the feed or hopper end. 60

As the crushed ore is fed from a suitable hopper (not shown) onto the feed end of the concentrating-pan power is applied from any desired source to the pulley E^X of the eccentric-shaft E, and the pan D is thereby vibrated from side to side, and the ore will gradually work its way down the pan, all of the heavy and valuable particles being shaken to bottom of the riffles D² and finding their way through the perforations D³. From thence 70 the concentrate falls upon the laterally-inclined washer-plate H, suitably supported in the framework, and is washed down said plate by means of a spray-pipe H'. 75

Having thus described my invention, what 80 I claim as new, and desire to secure by Letters Patent, is—

1. The improved ore-concentrator pan having its sides flared outward and bottom formed of an integral sheet bent or struck up into 85 straight, transverse, parallel ridges and grooves forming riffles, and having a series of holes in each riffle, and a series of triangular baffle-plates arranged oppositely, in pairs, and set vertically parallel with the riffles, and 90 extending from the sides inward toward each other, as shown and described.

2. The improved ore-concentrator composed of the pan having transverse riffles with perforations, flaring sides, and baffle-plates 95 arranged vertically as specified, a suitable frame, and swinging hangers for the pan, means for vibrating the pan transversely, the inclined plate arranged underneath the pan, and a water-discharge pipe extending across 100 the upper end of said plate and provided with openings, as shown and described.

In testimony whereof I have signed my name to this specification in the presence of two subscribing witnesses.

CHRISTOFFER A. CHRISTENSEN.
